Atteys

UNITED STATES PATENT OFFICE

ISAAC A. BAUM, OF CHICAGO, ILLINOIS

PLASTER-BOARD-FASTENING CLIP

Application filed October 3, 1928. Serial No. 310,048.

My invention relates to metal frames for wall openings and particularly to novel means for attaching plaster or wall board to such metal frames.

5 It is frequently desirable to utilize plaster board as a base for plaster applied to walls in which steel frames are utilized at the wall openings, and suitable means are necessary for attaching the boards at a 10 point over the metal frames.

Such means should be of relatively simple and economical construction in order that they may be applied economically and act as permanent and efficient holding devices.

15 A number of alternate forms of holding devices are illustrated in the accompanying drawings, in which

Fig. 1 is an elevation of a metal frame and fastening clip;

20 Fig. 2 is a sectional view on the line 2—2 of Fig. 1;

Fig. 3 is a sectional view on the line 3—3 of Fig. 1;

25 Fig. 4 is a sectional view showing a slightly modified form over that shown in the preceding figures;

Fig. 5 is an elevation of a further modification; and

30 Fig. 6 is a sectional view on the line 6—6 of Fig. 5.

Referring particularly to Figs. 1—3 inclusive, it will be seen that I have illustrated a metal frame member of generally channel shape having a web 10, side flanges 35 11, and a plaster terminal flange 12 with a rebent margin 13. As a means for anchoring the plaster on the face of the flange 11, I provide a plurality of loops 14 struck out of the metal of the flanges, the form of the 40 loops being best illustrated in Fig. 3. These are located in equally spaced relation from top to bottom of the frame. As a means for holding wall or plaster board, indicated at 15, I provide clips consisting of 45 a length of metal having legs 16 integral therewith and projecting diagonally downward from the sides, an end portion 17 that projects diagonally upwardly to a point beneath the margin 13 of the plaster terminal, 50 and a rear portion 18 adapted to overlie the

plaster board 15. A nail 19 may be driven through the clip, the plaster board and the flange if desired, or shorter nails or tacks may be used that merely extend through the clip and plaster board.

55

In use the clip is placed in the position shown in the drawings, and the board slid underneath the portion 18, the shoulder 20 preventing the board from being moved directly against the plaster anchor. When 60 in this position the nails may be driven.

In the construction shown in Fig. 4, the frame and plaster anchor are identical. However, the clip consists of a length of metal having a depressed metal portion adapted to underlie and interlock with the loop 14; a diagonally downwardly extending end portion 22 adapted to abut the flange 12 and an overhanging and rearwardly extending portion 23 that overlies 65 the plaster board 15. In this case the nail 24 may be extended through the clip and the plaster board and into the tile, indicated at 25. This construction is the same as that heretofore described except that the legs are omitted and the parts are held in position by the resiliency of the metal, the clip being originally shaped as indicated in dotted lines in Fig. 4. This necessitates the springing 70 upwardly of the portion 23 to admit the 75 plaster board therebeneath.

In the construction shown in Figs. 5 and 6, the frame element remains the same having a web 26, flanges 27 and plaster anchor 80 loop 28. However, a tongue or ear 29 is struck out of the flange 27 with the loop and lies in a plane with the top surface of the loop projecting laterally in the plane of the top surface of the plaster board 30. In 85 this form of metal frame wood blocks indicated at 31 are utilized as a support for wood trim and nails 32 may be passed through the clip 29 and the plaster board 90 into the wood block. The opening formed 95 by striking out the clip 29 permits the passage of the nail without interference with the metal of the flange 27.

Other forms of board holding clips may 100 be devised, but I do not wish to be limited

except as indicated in the appended claims.

I claim:

1. In combination, a frame having a flange adapted to lie parallel to the face of a wall, plaster anchors struck out from said flange, and a clip underlying and held by one of said plaster anchors and having a portion projecting laterally in the plane of the top surface of a wall board and adapted to be secured thereto.
- 10 2. In combination, a frame having a flange adapted to lie parallel to the face of a wall, anchor loops struck out from said flange, and a clip underlying and held by one of said anchor loops and having a portion projecting laterally in the plane of the top surface of a wall board and adapted to be secured thereto.
- 15 3. In combination, a frame having a flange adapted to lie parallel to the face of a wall, a rebent plaster defining portion formed along one edge of said flange, anchor loops struck out from said flange at intervals in the length thereof, and a clip underlying said anchor loops and engaging the rebent portion of said plaster defining portion at one end and adapted to overlie a plaster board at its other end.
- 20 4. Means for retaining a plaster board at its margin comprising in combination a metal frame element extending parallel to the face of a wall, a plaster defining portion formed at right angles to said flange on one margin thereof said plaster defining portion being rebent at its outer margin, anchor loops struck out of the metal in said flange at intervals in the length thereof, and a wall board retaining clip, said retaining clip being adapted to pass under said anchor loop and have contact at one end with the rebent plaster defining portion and at the other end to overlie said wall board.
- 25 40

In testimony whereof I have affixed my signature.

ISAAC A. BAUM.
